DESIGN FOR A BOX

Donald L. Gibb, Midland, Mich.

Application October 15, 1937, Serial No. 72,314

Term of patent 7 years

To all whom it may concern:

Be it known that I, Donald L. Gibb, a citizen of the United States, residing at Midland, in the county of Midland and State of Michigan, have invented a new, original, and ornamental Design for Boxes, of which the following is a specification, reference being had to the accompanying drawing, forming a part thereof.

I claim:

The ornamental design for a box, substantially as shown.

DONALD L. GIBB.
